ATTORNEYS.

UNITED STATES PATENT OFFICE.

HARRY B. LEEDY, OF PENDLETON, OREGON.

DERAIL LOCK.

Application filed June 27, 1921. Serial No. 430,528.

To all whom it may concern:

Be it known that I, HARRY B. LEEDY, a citizen of the United States, residing at Pendleton, in the county of Umatilla and State 5 of Oregon, have invented certain new and useful Improvements in Derail Locks, of which the following is a specification.

This invention relates to rail road safety appliances and has for its object to provide 10 a means to lock a derail in the open position until a car or train is safely past the derail.

A further object of the invention is to provide a means to lock an open derail until the train is safely past and hence to prevent 15 the derail being thoughtlessly thrown under a car and derailing it with damage to the car and a possible loss of life.

A further object of the invention is to provide a means for locking an open derail 20 that is automatic in its operation thus eliminating the human element.

A further object of the invention is to provide a means for locking a derail open which is simple to construct and install and which 25 is highly efficient in operation.

With these and other objects in view reference is now had to the accompanying drawings in which

Fig. 1 is a plan view of a portion of a 30 rail road showing the device installed;

Fig. 2 is an enlarged plan view of a derail in a closed position;

Fig. 3 is a side elevation of Fig. 2;

Fig. 4 is an enlarged plan view of a derail 35 in an open position;

Fig. 5 is a side elevation of Fig. 4;

Fig. 6 is a perspective view of the device;

Fig. 7 is a front sectional view of the 40 bar and yielding crank hinge; and

Fig. 8 is a front sectional view of a plain crank hinge.

Having reference to the drawings like numerals refer to like parts throughout and 45 the numeral 1 refers to a rail road consisting in part of a main track 2, a passing track 3, a switch head 4 which is of the usual type, and other parts which will be designated by numerals as the description 50 proceeds.

The passing track 3 consists of a tangent 5, an outer curved rail 6 and an inner curved rail 7, the curved rails forming a juncture with the main track by the proper throwing

of the switch 8 which is here shown closed 55 against the passing track.

In mountainous districts, where passing tracks are required, it has been found necessary to provide a means to prevent a car or train backing by gravity out through the 60 switch 8 and onto the main track 2, and the most practical device in use is the derail 9 (here shown closed) which is positioned ordinarily at the beginning of the curved rail 6 as at this point the flange of the wheel 65 10 bears against the rail as it leaves the tangent and changes direction and hence is less liable to strike against an open derail 11 with possible damage.

The derail is connected to and operable 70 by means of the switch through the switch rod 12, the connecting rod 13, the rod 14, and the bell cranks 15, so that opening the switch onto the passing track opens the derail and provides a clear track for the train. This 75 type of derail is termed a mechanically operated derail, and being in general use no further description as to its specific operation is deemed necessary.

As soon as the train passes fully onto the 80 tangent the switch is thrown to clear the main track and the derail is closed, hence should a car or train start backing the wheel would strike against the derail, which as its name implies would derail the train, 85 and the derailment would occur on the side of the track away from the main line, due to the location of the derail which is at the beginning of the curve.

As the derail is approximately 50 yards 90 from the switch head, and as the switch must remain open until the last wheels of the last car has passed the open derail, and as there is a tendency on the part of the switchman to close the switch that he may 95 catch the rear end of the train before it has gone far this being the usual custom in level parts of the country which predominates, it is obviously necessary to maintain the derail in the open position until the last car 100 passes which is accomplished by my derail lock consisting of a bar 16 positioned parallel and adjacent to the rail 6, with one of its ends 17 resting normally within engageable proximity to one wing 18 of the 105 derail. The bar has a length equalling the wheel base of the longest car and is normally positioned so that the top of the bar

is approximately flush with the top of the rail; thus the flange of the wheel will depress the bar so that the end 17 will engage the wing 18 and the derail cannot be closed 5 until the last wheel is passed.

Obviously the bar must be maintained in a uniformly horizontal position to cause the end 17 to engage the wing 18 with the pressure of the flange of the wheel at any point 10 on the bar, hence to accomplish this I use a device which I term a crank hinge 19 consisting of a plate 20, which may be suitably spiked or otherwise fastened to a tie 21, having a pair of uprights 22 in which is rotatably mounted a crank 23, which in turn rotatably engages the bar 16, as plainly shown in Fig. 7.

To restore the bar to its normal position one or more of the crank hinges is provided 20 with a spring 24, shown in Fig. 7, in which case a top 25 is provided to protect the spring from dirt or other matter that might obstruct its movement.

As it is deemed best to have the bar 16 25 operate in one direction at all times regardless of the direction in which the train is moving I have provided an auxiliary bar 26 having curved ends 27 wherewith to receive the impact of the wheel gradually, and 30 this auxiliary bar while moving in one direction will impart a contrary motion to the bar 16 by means of the toggle 28 and the cross bar 29. The auxiliary bar is attached to the ties in a similar manner to that of 35 the bar 16.

It will now be seen that with the switch 8 opened to the passing track 3 the train will pass onto the curved rails 6 and 7 and the flange of the wheel 10 will engage and 40 depress the bar 16 until the end 17 closes down against the derail 11 which has been opened by the throwing of the switch. The derail now must remain in the open position until the train has passed the derail when the 45 switch may be closed.

Now when a train is to back down onto the main track the switch is opened, the derail opening with it, and the first wheel of the train engages the auxiliary bar 26 which

is depressed and which now depresses the 50 bar 16, after which the wheels resting on the bar 16 maintains it in the depressed position locking the derail as before.

Having thus described my invention, I claim

55

1. In a derail lock, in combination with a derail and an automatic locking means operable by means of a train in the direction of and to rest upon an open derail.

2. In a derail lock, the combination of a 60 derail and an automatic locking means consisting of a depressible bar, mounted adjacent to one rail of a rail road, and positioned to engage the open derail when said bar is depressed, and an auxiliary bar operably 65 attached to said bar.

3. In a derail lock, the combination of a 70 derail and an automatic lock consisting of a depressible bar mounted parallel and adjacent to one rail of a rail road, and positioned to engage the open derail when said bar is depressed, crank hinges yieldingly attached to and supporting said bar, and an auxiliary bar operably attached to said rail road adjacent to the other rail thereof, and 75 means to operably unite said auxiliary bar and said bar.

4. In a derail lock, the combination of a 80 derail and an automatic lock consisting of a depressible bar, yieldingly and hingedly attached to a railroad and positioned parallel and adjacent to one rail thereof, with one of its ends resting normally within engageable proximity to said derail, an auxiliary bar positioned opposite to said derail, 85 and means to operably unite said auxiliary bar and said bar.

5. In a derail lock, the combination of a 90 derail and automatic lock consisting of a depressible bar positioned parallel to one rail of a rail road and adjacent to said derail, a plurality of yielding crank hinges rotatably attached to said bar to maintain a uniformly horizontal position thereto, and an auxiliary bar connected to, operable with, 95 and positioned opposite to said bar.

In testimony whereof I affix my signature.
HARRY B. LEEDY.
